(57) **CLAIM**

The ornamental design for a zipper pull tab, as shown and described.

DESCRIPTION

FIG. 1 is a top isometric view of a zipper pull tab shown with zipper pull and myAirfeet.com logo, wherein the zipper pull and Airfeet.com artwork are shown by dashed broken lines. The dashed broken lines showing the zipper pull and myAirfeet.com logo are for the purpose of illustrating portions of the use model of the zipper pull tab and form no part of the claimed design. The myAirFeet.com logo shown in the reproductions, and forming no part of the claim, is a registered trademark of AirFeet LLC.

FIG. 2 is a top isometric view of the zipper pull tab shown with zipper pull and artwork in a neutral configuration.

FIG. 3 is a top view of the zipper pull tab in a neutral configuration.

FIG. 4 is a bottom view of the zipper pull tab in a neutral configuration.

FIG. 5 is a right-side view of the zipper pull tab in a neutral configuration.

FIG. 6 is a left-side view of the zipper pull tab in a neutral configuration.

FIG. 7 FIG. 7 is a back-side view of the zipper pull tab in a neutral configuration.

FIG. 8 FIG. 8 is a front-view view of the zipper pull tab in a neutral configuration.

FIG. 9 is a top view of the zipper pull tab in a looped configuration.

FIG. 10 is a bottom view of the zipper pull tab in a looped configuration.

FIG. 11 is a right-side view of the zipper pull tab in a looped configuration.

FIG. 12 is a left-side view of the zipper pull tab in a looped configuration.

FIG. 13 is a back-side view of the zipper pull tab in a looped configuration; and,

FIG. 14 is a front-view view of the zipper pull tab in a looped configuration.
